UNITED STATES PATENT OFFICE.

HENRY L. ROBERTS, OF GRIMSBY, ONTARIO, CANADA.

PACKING-CASE.

1,071,090.

Specification of Letters Patent. Patented Aug. 26, 1913.

Application filed October 12, 1912. Serial No. 725,436.

To all whom it may concern:

Be it known that I, HENRY LUCAS ROBERTS, a subject of the King of Great Britain, and a citizen of the Dominion of Canada, 5 residing at Grimsby, in the county of Lincoln, in the Province of Ontario, Dominion of Canada, have invented certain new and useful Improvements in Packing-Cases, of which the following is a specification.

10 My invention relates to packing cases and more particularly to those intended for packing fragile articles for transit over long distances.

The main object of my invention is to provide a packing case especially useful for perishable fruits and similar articles.

A further object of my invention is to furnish a packing case in which every article packed therein is effectively prevented 20 from coming into contact with the adjacent or surrounding article or articles.

A still further object of my invention is to provide a packing case through which the air can freely circulate an exceedingly desirable feature where rapidly perishable fruits are concerned.

With these objects in view, my invention consists essentially of a skeleton case or crate 30 fitted internally with a series of spaced supports and flexible containers for the articles to be packed, said supports and containers being arranged honey-comb fashion.

The accompanying drawing illustrates, by way of example, one convenient embodiment 35 of my invention.

Figure 1, is a side elevation of a packing case suitable for peaches and similar perishable fruits, with part broken away or in section for the sake of clearness; and Fig. 40 2, is an end view of the same with the right hand half similarly broken away.

According to the form of my invention illustrated I construct the case proper from a series of spaced, longitudinally arranged, 45 strips *a*, *a*, of suitable material, which are laterally braced and firmly secured to rectangularly shaped battens or frames *b*, *b*. On an inspection of Fig. 1, it will be seen that the strips *a*, *a*, are slightly shorter in 50 length than the distance over the extreme ends *c*, *d*, of the battens *b*, *b*, so that a sort of recess is formed at each end of the case.

e, *e*, are spaced supports of suitable material—millboard or the like—and dimensions to fit easily within the case, and they 55 are each pierced by a series of registering

and appropriately arranged holes *f*, *f*, for the purpose hereinafter explained. *g*, *h*, are similarly constructed end supports of suitable dimensions to fit the ends *c*, *d*, respectively. *i*, *j*, are end boards or closing-in pieces of stout material which are likewise pierced by a series of elongated or thimble shaped apertures *k*, *k*, adapted to register with the holes *f*, *f*, above referred to.

l, *l*, are thin canvas tubes each of which is more than double the length of the packing case, and they are adapted to be easily threaded through the holes *f*, *f*, and apertures *k*, *k*, hereinbefore described.

In use, and assuming, as shown, that the case is to contain sixteen rows constituted by eight lengths of canvas tubing, the packer takes the end board *j*, for instance, and threads the ends of each canvas tube *l*, *l*, 70 through two adjacent apertures *k*, *k*, until the length of said tube is equally divided on one side thereof and the middle portion *m*, is taut between the said apertures *k*, *k*, on the other side. The free ends of said tubes *l*, *l*, are then drawn through the registering holes *f*, *f*, of the end support *h*, until the said support *h*, abuts the end board *j*. The said parts are then placed in position within the end *d*, with the nest of tubes *l*, *l*, inside 80 the case. The case is now turned vertical with the end *d*, downward, or on the ground. The packer takes each tube *l*, consecutively and inserts a peach *n*, therein lowering same down until it adjoins the end support *h*. 90

When this operation is completed a support *e*, is threaded down the nest of tubes by drawing each said tube through the registering and corresponding holes *f*, *f*, until it closely adjoins the layer of peaches *n*, *n*, 95 another layer of peaches *n*, *n*, is thereupon inserted in the tubes *l*, *l*, and the second support *e*, placed *in situ*. This operation is continued until the entire case is filled whereupon the end support *g*, and end *i*, 100 are fitted in place as described with reference to the parts *h*, *j*, only in a reverse order. The ends of each tube *l*, are then brought together and knotted or otherwise secured tightly to prevent their being drawn 105 into the case which is now ready for shipment.

From the foregoing it will be readily seen that by my invention I dispense with the necessity of wrapping each separate article in 110 paper, as well as the use of "excelsior" or similar packing material, and that the ar-

ties are more expeditiously and safely packed. Perfect ventilation is insured, and whereas under the existing method of packing when one article—a fruit for instance—
5 gets damaged or decomposes with a consequential contamination or decay of the surrounding articles, by my invention such a possibility is effectively eliminated as the separate articles cannot touch each other.
10 Furthermore where perishable articles are shipped long distances my invention provides a secure and simple means for so packing the said articles that their safe transit is insured.
15 Changes in the details of construction of the several parts as well as other combinations and arrangements of the same will be self evident to adapt my invention to different uses and requirements, and I wish it
20 clearly understood that the form described and shown is by way of example only.
Having thus described my invention, what I claim as new, is:—

1. A packing case comprising a skeleton frame and holed end closing-in pieces, a series of spaced partitions arranged at equal distances apart intermediate said end closing-in pieces and disposed transversely of

the skeleton frame intermediate the end closing-in pieces and said spaced partitions 30 being holed to register with the end pieces, flexible tubes threaded through alining holes, parallel to one another longitudinally of the skeleton frame, the ends of said tubes being secured together, substantially as described for the purpose set forth. 35

2. A packing case comprising a skeleton frame, end closures for the opposite ends of said frame, said closures having alining holes formed therethrough, spaced, plane, 40 perforate partitions conforming in outline to the interior shape of said frame and arranged therein, and a plurality of flexible tubular members threaded through said end closures and through said partitions, each 45 of said tubular members extending all the way through said frame in one direction and being returned through said frame in the opposite direction with its two ends terminating adjacent each other. 50

Signed at Hamilton, Ontario, Canada,
this 10th day of September, A. D. 1912.

H. L. ROBERTS.
